SKI BOOT

Alden B. Hanson and Chris A. Hanson, Boulder, Colo.,
assignors to Hanson Industries Inc., Boulder, Colo.

Filed Mar. 1, 1972, Ser. No. 331,085

Term of patent 14 years

Int. Cl. D2—04

U.S. Cl. D2—276

FIG. 1

FIG. 2

FIG. 5

FIG. 6

FIG. 1 is a side elevational view of a ski boot embodying our new design;

FIG. 2 is a side elevational view of the other side;

FIG. 3 is a rear elevational view thereof;

FIG. 4 is a front elevational view;

FIG. 5 is a top plan view;

FIG. 6 is a bottom plan view; and

FIG. 7 is a side elevational view of a second embodiment of the design of FIG. 1 wherein the ski boot has only one buckle fastener.

We claim:

The ornamental design for a ski boot, as shown and described.
